(57) **ABSTRACT**

A new and distinct cultivar of *Dahlia* plant named 'Dodahhypel 22', characterized by its broadly upright and uniformly mounding plant habit; moderately vigorous growth habit and moderate growth rate; strong branching habit; dark green-colored leaves; freely flowering habit; large double-type inflorescences with bright yellow-colored ray florets; good postproduction longevity; and good garden performance.

1 Drawing Sheet

1

Botanical designation: *Dahlia variabilis*.
Cultivar denomination: 'DODAHHYPYEL 22'.

CROSS-REFERENCED TO CLOSELY-RELATED APPLICATIONS

An European Community Plant Breeder's Rights application for the instant plant was filed by the Applicant/Assignee, Dümmen Group B.V. of De Lier, The Netherlands on Feb. 23, 2022, application number 2022/0326. Foreign priority is not claimed to this application.

BACKGROUND OF THE INVENTION

The present invention relates to a new and distinct cultivar of *Dahlia* plant, botanically known as *Dahlia variabilis* and hereinafter referred to by the name 'Dodahhypel 22'.

The new *Dahlia* plant is a product of a planned breeding program conducted by the Inventors in Hillegom and De Lier, The Netherlands. The objective of the breeding program is to create new container *Dahlia* plants that have a freely branching and flowering habit, dark-colored leaves, large attractive inflorescences and good postproduction longevity.

The new *Dahlia* plant originated from a cross-pollination during the autumn of 2017 in Hillegom, The Netherlands of two unidentified proprietary selections of *Dahlia variabilis*, not patented. The new *Dahlia* plant was discovered and selected by the Inventors as a single flowering plant from within the progeny of the stated cross-pollination in a controlled greenhouse environment in Hillegom, The Netherlands during the summer of 2018.

Asexual reproduction of the new *Dahlia* plant by vegetative terminal cuttings in a controlled greenhouse environment in De Lier, The Netherlands since the autumn of 2018

2

has shown that the unique features of this new *Dahlia* plant are stable and reproduced true to type in successive generations.

5 SUMMARY OF THE INVENTION

Plants of the new *Dahlia* have not been observed under all possible combinations of environmental conditions and cultural practices. The phenotype may vary somewhat with variations in environmental conditions such as temperature and light intensity, without, however, any variance in genotype.

The following traits have been repeatedly observed and are determined to be the unique characteristics of 'Dodahhypel 22'. These characteristics in combination distinguish 'Dodahhypel 22' as a new and distinct *Dahlia* plant:

1. Broadly upright and uniformly mounding plant habit.
2. Moderately vigorous growth habit and moderate growth rate.
3. Strong branching habit.
4. Dark green-colored leaves.
5. Freely flowering habit.
6. Large double-type inflorescences with bright yellow-colored ray florets.
7. Good postproduction longevity.
8. Good garden performance.

Compared to plants of the parent selections, plants of the new *Dahlia* differ primarily in growth habit as plants of the new *Dahlia* are more uniformly branching and mounding than plants of the parent selections.

Plants of the new *Dahlia* can be compared to plants of *Dahlia variabilis* 'Hypnotica Lemon Swirl', not patented. In side-by-side comparisons, plants of the new *Dahlia* differ primarily from plants of 'Hypnotica Lemon Swirl' in the following characteristics:

Post-production longevity.—Inflorescences maintain good substance for about two to three weeks on the plant; inflorescences persistent.

Inflorescence buds.—Height: About 1 cm. Diameter: About 1 cm. Shape: Globular. Texture and luster: 5 Smooth; glossy. Color: Close to 144B.

Inflorescence size.—Diameter: About 9.5 cm. Depth (height): About 5 cm. Disc diameter: About 1 cm. Receptacle height: About 5 mm. Receptacle diameter: About 1.7 cm. Receptacle color: Close to 144B. 10

Ray florets.—Quantity per inflorescence: About 80 to 90 arranged in about eight whorls. Length: About 5 cm. Width: About 3 cm. Shape: Lanceolate. Apex: Obtuse. Base: Cuneate. Margin: Entire. Aspect: Initially upright to roughly perpendicular to the 15 peduncle; somewhat concave. Texture and luster, upper and lower surfaces: Smooth, glabrous; matte. Color: When opening and fully opened, upper surface: Close to 2A; venation, close to 2A; color becoming closer to 1A with subsequent development. When opening and fully opened, lower surface: Close to 1A; venation, close to 1A; color does not change with subsequent development.

Disc florets.—Quantity per inflorescence: About 50 to 60; disc florets are inconspicuous. Length: About 1.2 cm. Diameter: About 3 mm. Shape: Tubular, elongated; apices obtuse. Texture and luster: Smooth, glabrous; matte. Color, when opening and fully opened, inner and outer surfaces: Close to 1B. 20

Phyllaries.—Quantity per inflorescence: About six 30 arranged in a single whorl. Length: About 2.5 cm. Width: About 1 cm. Shape: Lanceolate. Apex: Acute. Base: Cuneate. Margin: Entire. Texture and luster,

upper and lower surfaces: Smooth, glabrous; matte. Color, upper and lower surfaces: Close to 137A; venation, close to 137A.

Peduncles.—Length, terminal peduncle: About 6.5 cm. Diameter, terminal peduncle: About 4 mm. Aspect: Mostly erect to slightly outwardly. Strength: Moderately strong. Texture and luster: Smooth, glabrous; semi-glossy. Color: Close to 144B.

Reproductive organs.—Androecium: Present on disc florets only. Stamen quantity per floret: One. Filament length: About 1.1 cm. Filament color: Close to 4D. Anther size: About 4 mm by 5 mm. Anther color: Close to 17B. Pollen amount: Moderate. Pollen color: Close to 17A. Gynoecium: Present on disc florets only. Pistil quantity per floret: One. Pistil length: About 1.3 cm. Style length: About 1.1 cm. Style color: Close to 144D. Stigma diameter: Less than 1 mm. Stigma shape: Round. Stigma color: Close to 144C. Ovary color: Close to N144C. Seeds: To date, seed development has not been observed on plants of the new *Dahlia*.

Pathogen & pest resistance: To date, plants of the new *Dahlia* have not been observed to be resistant to pathogens and pests common to *Dahlia* plants.

Temperature tolerance & garden performance: Plants of the new *Dahlia* tolerate high temperatures about 35° C. and short periods of low temperatures about 5° to 10° C. Plants of the new *Dahlia* have been observed to have good garden performance.

It is claimed:

1. A new and distinct *Dahlia* plant named 'Dodahhypylel 22' as illustrated and described.
